UNITED STATES PATENT OFFICE.

LOUIS FRIEDMANN, EMANUEL BLAUHORN, AND HANS DEUTSCH, OF VIENNA,
AUSTRIA.

EXHAUST-STEAM INJECTOR.

Application filed August 11, 1924. Serial No. 731,285.

To all whom it may concern:

Be it known that we, LOUIS FRIEDMANN, manufacturer, EMANUEL BLAUHORN, manager, HANS DEUTSCH, engineer, citizens of the Austrian Republic, residing at Vienna, in the Republic of Austria, have invented certain new and useful Improvements in Exhaust-Steam Injectors, of which the following is a specification.

10 This invention relates to exhaust steam injectors of the type which may be operated by exhaust steam and live steam simultaneously as well as with live steam alone.

15 It essentially consists in an arrangement whereby the shutting off members for the exhaust steam and for the water supply are controlled by the steam pressure.

20 In particular the invention comprises automatic means controlled by the steam pressure which are capable of shutting off the exhaust steam branch leading to the steam chamber of the injector when the injector is fed with live steam alone.

25 According to the invention these automatic means consist of two non-return valves cooperating with each other, each of these valves forming a stop for the other valve, when it is resting on its seat.

30 Another feature of the invention consists in providing a live steam supply for feeding the exhaust steam cone of the injector and an additional live steam supply for applying steam pressure to said automatic means and a distributing member for the alternate admission of live steam to the one or other of the said supply pipes. Another feature of the invention consists in controlling the water supply to the injector by means of the live steam supplied to the live steam cone of the injector. In particular this control may be effected by a valve or other means arranged in the path of the live steam or in a room or chamber communicating therewith and capable of transmitting its motion to the water supply valve. This valve may also control a passage arranged between the path of the live steam or the room or chamber communicating therewith and the water supply chamber of the injector.

35 A further feature of the invention consists in arranging the water inlet to the water chamber surrounding the exhaust steam cone of the injector in such a manner

that it will be located above the axis of the 55 exhaust steam cone.

A further feature of the invention consists in that the casing of the injector is divided into two separate parts along a plane perpendicular to the axis of the cones, 60 one of said parts containing the live steam cone, the exhaust steam cone and the mixing cone, while the other part contains the collecting cone and the delivery cone.

Further features will appear from the following detailed description of several modifications of the invention.

The accompanying drawings show two different modifications of the invention when applied to an exhaust steam injector for 70 locomotives.

In the arrangement shown in Fig. 1, A is the injector casing, which consists of two parts 1 and 2 which may be manufactured separately and are afterwards connected by 75 means of flanges or the like. 3 indicates the steam chamber of the injector, 4 is the water chamber and 5 the overflow chamber, 6 indicates the delivery chamber, 7 is the live steam cone, 8 the exhaust steam cone and 80 9 and 10 are the mixing cones. The injector moreover comprises a collecting cone 11 and a delivery cone 12. The exhaust steam is supplied by means of an exhaust steam branch 13 which leads to an exhaust steam admission chamber 14. A non-return valve 15 hereinafter called the exhaust steam admission valve is arranged within 85 said room by means of which the steam chamber 3 may be effectively shut off from the admission chamber 14 and the exhaust steam branch 13. A pipe 16 hereinafter called "the pressure pipe" is arranged through which live steam from the locomotive boiler from the main steam pipe leading to the steam cylinders or from the steam chest may be admitted. The pressure pipe 16 leads to a chamber 17 in which a second non-return valve 18 hereinafter called "the exhaust steam control valve" is arranged. In the arrangement shown in Fig. 1 the chamber 17 is in communication with the exhaust steam admission chamber 14 by means of a passage 19, when the exhaust steam control valve 18 is lifted from 90 its seat. The steam chamber 3 or the exhaust steam branch 13 and the exhaust steam admission chamber 14 respectively are, how-

eyer, shut off from the room 17 when the exhaust steam controlling valve is pressed against its seat and thus shuts the passage 19. The non-return valves 15 and 18 are arranged in such a manner that whenever one of them rests on its seat, it forms a stop of the other valve and prevents it from coming down on its seat. One of the said non-return valves is therefore lifted, when the other is in its shut-off position. If for instance the pressure exerted on the non-return valve 15 independently of the fact whether this pressure is due to a weight or a spring or to the steam in the branch 13 or chamber 14 is greater than the pressure on the non-return valve 18 then the non-return valve 15 is closed, while the non-return valve 18 is lifted and frees the passage 19, so that the fluid or medium contained in the pipe 16 for instance the condensate formed therein may freely escape. If equal pressures prevail in the chambers 17 and 14 then the valve 15 rests on its seat and the valve 18 is lifted. The valve 15 may as shown in Fig. 1 be pressed upon its seat either by spring pressure or by means of its own weight or by both.

A second live steam pipe 20, hereinafter called "the auxiliary live steam pipe" is provided by means of which live steam from the boiler may penetrate into the steam chamber 3. As this live steam supply is only intended to form a substitute for the exhaust steam during the time intervals, within which no exhaust steam is available, it is necessary to reduce its pressure before admitting it to the steam chamber and this is preferably done by throttling the steam already before it enters the auxiliary branch 20 by means of a reduced cross section at its inlet. As shown in Fig. 1 the steam thus conveyed to the steam chamber may enter the said chamber through a series of apertures 30 made in the wall of the branch 20 within the steam chamber.

The two live steam pipes 16 and 20 can only alternately be closed and opened by means of a distributing member 21. This distributing member is represented in Fig. 1 as a piston valve, but of course also other distributing members such as conchoidal slide valve, a flat valve or a valve of the lift type or any other structure can be employed for this purpose.

The live steam cone 7 of the injector is supplied with live steam during the operation of the injector by a separate live steam branch 22 called "the main live steam branch" which may be set in communication with the steam boiler. As shown in Fig. 1 a channel or passage 23 branches off from the main live steam branch 22 and leads to a chamber 24 in which a valve 25 of the lift type is arranged, hereinafter called "the water supply control valve". The said

valve controls a passage 26 leading to the water chamber 4 of the injector. It is pressed against its seat under the influence of the steam entering the main live steam pipe 22 and thereby also the room or chamber 24 by means of the passage 23. When thus moved against its seat it transmits its motion to the water admission valve 27, which is thereby opened and frees the passage of the water coming through pipe 28 from the tender of the locomotive, so that the water may enter the water chamber 4. The feed water of the injector as shown enters the water chamber 4 surrounding the exhaust steam cone 8 from above. This way of feeding the water from above influences the operation of the injector and many tests have shown that the injector will operate more easily and efficiently and is more easily started with such an arrangement than with the known arrangements where the water is supplied from below the annular space 4.

An exhaust steam injector by virtue of the fact that it contains a greater number of cones, also has a greater constructional length from end to end. Moreover it is well known that a strict coincidence of the axes of the several cones is necessary to ensure a good working of the same. Now it has been found that though it is of utmost importance that the live steam nozzle 7, the exhaust steam nozzle 8 and the mixing nozzle 9 adjacent to it, have strictly coincident axes and that the same condition exists as regards the collecting cone 11 and the delivery cone 12. Such a strict coincidence of the axes of the mixing nozzles 9 and 10 and of the collecting nozzle 11 is not vital, as the injector is not as sensitive against small inaccuracies at this place, as it is against the smallest inaccuracy at another place. This fact, which we have discovered, therefore allows to divide the injector in such a manner that each of the two parts contains the nozzles which should have a strict coincidence of the axes. The remaining nozzles may then be located in the one or the other part as the case may be. The division of the casing is therefore made in such a manner, that one part 1 contains the cones 7, 8 and 9 while the other part 2 contains the cones 11 and 12. The cone 10 may be located in either part.

This division of the injector has the great advantage that in each of the two parts of the injectors the threads or guides of the cones may be turned or bored from one side only, whereby a much greater accuracy in the coincidence of the axes of the boreholes or screw-threads may be obtained for the several nozzles just at the places, where such accuracy is required.

The modification of the apparatus shown in Fig. 2 is in most respects similar to that shown in Fig. 1. It differs from it, how-

ever in the location and arrangement of the exhaust steam control valve 18 which is situated below the exhaust steam shut-off valve and is capable of lifting the same by means of the spindle or projection attached to it. The non-return valve 15 forming the exhaust steam admission valve is kept on its seat by its own weight, which may be conveniently adjusted by filling its central bore

10 with particles of heavy material. The aperture 19 in this case leads directly to the steam chamber 3 and not only to an admission room.

Likewise the auxiliary live steam pipe 20 carrying the live steam capable of substituting the exhaust steam, if need be, discharges directly into the steam chamber 3. It is also provided with means reducing the steam pressure at its upper end. Moreover the 20 main live steam branch 22 carrying live steam permanently during the operation of the injector leads directly to the chamber 24 which it has to traverse while flowing to the live steam cone. Thus the valve 25 controlling the water admission valve is directly influenced and moved by the live steam flowing through the main live steam pipe 22 to the live steam cone 7 and the arrangement may be thus that live steam in greater quantities 30 only enters the cone, when the valve 25 has been moved against its seat.

The operation of the improved injector is the following: Assuming that feeding of the boiler through the injector should 35 take place during the stoppage of the engine, the distributing member 21 is brought in the position shown in which the live steam pipe 16 is shut off. Then the steam admission valve 29 for the steam from the 40 boiler is opened. The live steam from the boiler then enters the main live steam pipe 22 and from there flows to the live steam cone 7. In the arrangement according to Fig. 1 the said live steam will penetrate 45 through the passage 23 and act upon the non-return valve 25 thereby opening the water admission valve 27.

In the arrangement shown in Fig. 2 the live steam on its way to the steam cone 7 will immediately act upon the water admission control valve 25. Moreover live steam will also enter the auxiliary live steam pipe 20 but with reduced pressure as it is throttled by the reduction of the cross 55 section at the entrance of said pipe and from there penetrates to the steam chamber 3, from whence it will pass into the exhaust steam nozzle 8 and into the mixing nozzle 10. In that part of the steam chamber 60 which lies behind the live steam cone a depression will prevail during the working of the apparatus and consequently the exhaust steam admission valve 15 is pressed down upon its seat and the entrance of steam 65 or waste gases into the steam chamber 3

through the exhaust steam branch 13 is prevented. The depression in the steam chamber 3 may even be very low or may disappear altogether. Nevertheless any entrance of waste gases or steam from this side is 70 prevented as the valve is held upon its seat by its own weight or by spring pressure as shown.

If on the other hand feeding of the boiler has to take place during the running of 75 the engine, the distributing member 21 is brought into the position, where it blocks the entrance to the auxiliary steam pipe 20 but frees the pressure pipe 16. If now the steam valve 29 is opened then the steam 80 from the boiler will penetrate to the live steam cone 7 through pipe 22 as before, but will now enter the pressure pipe 16 and penetrate to the chamber 17. The pressure of the live steam now acting on the exhaust 85 steam controlling valve 18 this valve will be moved against its seat and will thereby open the exhaust steam admission valve 15, thus permitting the admission of exhaust steam to the steam chamber. The working 90 of the injector itself is well known in the art and need not be described. We do not limit ourselves to the modifications shown as the various parts of the invention may be modified in various ways without departing from the essence of the invention. 95

What we claim is:

1. An injector of the character described comprising an exhaust steam cone, an exhaust steam branch, a non-return valve 100 opening into the exhaust steam branch for controlling the admission of exhaust steam therefrom to said exhaust steam cone, a second non-return valve co-operating with the first said valve and capable of transmitting its movement thereto, and means for subjecting said second non-return valve to the action of live steam pressure. 105

2. In an injector of the character described, a live steam cone and an exhaust steam cone, a steam chamber in communication with the exhaust steam cone, means to supply said steam chamber with exhaust steam comprising an exhaust steam branch and an exhaust steam admission chamber, 110 a non-return valve for controlling the admission of exhaust steam from said exhaust steam branch and admission chamber to the first said steam chamber and opening into said exhaust steam admission chamber, a 115 second non-return valve cooperating with the first said valve and adapted to control the same, and a separate pressure branch to apply the pressure of the live steam to said second non-return valve for operating it. 120

3. In an injector of the character described, a live steam cone and an exhaust steam cone, means for alternately supplying live steam and exhaust steam to said exhaust steam cone, a non-return valve control- 125 130

ling the admission of the exhaust steam thereto, a pressure pipe and a second non-return valve therein controlling the first non-return valve and a distributing member allowing only alternate admission of live steam to the pressure pipe and to the exhaust steam cone.

4. In an injector of the character described, a live steam cone and an exhaust steam cone, a steam chamber in communication with the exhaust steam cone, a main live steam branch for supplying the live steam cone with live steam, an exhaust steam branch for supplying exhaust steam to said chamber, an auxiliary live steam branch for admitting live steam to said chamber, a non-return exhaust steam admission valve for controlling the admission of exhaust steam to said chamber and a second non-return valve controlling the exhaust steam valve, a pressure pipe arranged to carry live steam to said second valve, and a distributing member for allowing only alternate admission of live steam to said pressure pipe and to said auxiliary live steam branch.

5. In an injector of the character described, an exhaust steam cone and means to supply it with exhaust steam, a non-return valve to control the admission of exhaust steam, a second non-return valve cooperating therewith and operated by live steam pressure, each non-return valve forming a stop for the other when resting upon its seat.

6. In an injector of the character described, an exhaust steam cone and means to supply live steam and exhaust steam thereto, a non-return valve for controlling the admission of exhaust steam to said cone, a pressure pipe, means for admitting live steam alternately to said pressure pipe and to the exhaust cone, a second non-return valve arranged within said pressure pipe and cooperating with the first non-return valve, each non-return valve forming a stop for the other when resting upon its seat.

7. In an injector of the character described, an exhaust steam cone and a steam chamber communicating therewith, said steam chamber being in its turn in communication with an exhaust steam supply branch, a non-return valve within said exhaust steam branch and opening into the same, a pressure pipe leading to an opening in communication with said steam chamber, and a controlling non-return valve within said pressure pipe cooperating with the first non-return valve and closing said communication when live steam pressure is applied to the pressure pipe.

8. In an injector of the character described, an exhaust steam cone and a steam chamber communicating therewith, an exhaust steam branch leading to said steam chamber, a pressure branch leading to an

opening adapted to communicate with said steam chamber, a non-return valve within the exhaust steam branch and opening into the same, a second non-return valve, operated by the live steam pressure within said pressure branch and adapted to control said opening, said valve cooperating with and adapted to open said first non-return valve when it is closed and close the communication of the pressure branch with the steam chamber when the first non-return valve is opened.

9. In an injector of the character described, a live steam cone and an exhaust steam cone, a main live steam branch for supplying live steam to said live steam cone, a water chamber and a valve controlling the admission of water to said chamber, and a second valve controlled by the steam pressure in the main live steam branch for controlling the operation of said water admission valve.

10. In an injector of the character described, an exhaust steam cone and a steam chamber communicating therewith, an exhaust steam branch leading to said steam chamber, a pressure pipe leading to said steam chamber, a nonreturn valve adapted for shutting off the steam chamber from said exhaust branch, a second non-return valve adapted for shutting off the pressure pipe from said steam chamber both non-return valves being arranged to cooperate with each other and each forming a stop for the other when resting upon its seat.

11. In an injector of the character described, an exhaust steam cone and a steam chamber communicating therewith, an exhaust steam branch and a pressure branch both adapted to communicate with said steam chamber, a non-return valve opening into said exhaust steam branch adapted to shut the communication between the same and the steam chamber, a second non-return valve adapted to shut the communication between the pressure pipe and the steam chamber, both non-return valves cooperating with each other and adapted to form a stop for the other when pressed against their seats.

12. In an injector of the character described, a live steam cone and an exhaust steam cone, a main live steam branch for supplying live steam to said live steam cone, a water chamber surrounding said exhaust steam cone, a valve for controlling the admission of water to said chamber, a second valve exposed to the steam pressure of said live steam branch, and an operative connection between the two valves for providing a positive control for the opening movement of the water admission valve when the controlling valve is exposed to the live steam pressure.

13. In an injector of the character described, a live steam cone and an exhaust

- steam cone, a main live steam branch for supplying live steam to said live steam cone, a water chamber surrounding said exhaust steam cone, a valve for controlling the admission of water to said chamber, an opening establishing a communication between said live steam branch and the water chamber, a second valve for controlling said opening exposed to the steam pressure in the live steam branch, and an operative connection between the two valves for providing a positive control of the opening movement of the water admission valve under the influence of the steam pressure in the live steam branch.
14. In an injector of the kind described, a live steam cone and an exhaust steam cone, a live steam branch to supply live steam to said live steam cone, a water chamber surrounding the exhaust steam cone and a valve for controlling the admission of water to said water chamber, an opening establishing a communication between said live steam branch and said water chamber, a controlling valve exposed to the steam pressure in the live steam branch for said opening between said live steam branch and the water chamber, said valve adapted to close said opening when the steam pressure in the live steam branch exceeds a certain value and an operative connection between said controlling valve and said water admission valve adapted to positively open the latter valve when the controlling valve is moved to the position for closing the opening leading to the water chamber.
15. In an injector of the character described, a live steam cone and an exhaust steam cone, a water chamber surrounding the exhaust steam cone, and a water inlet opening into said chamber above the axis of the exhaust steam cone.
16. In an injector of the character described, a live steam cone and an exhaust steam cone, a live steam branch for supplying live steam to said live steam cone, a water chamber surrounding the exhaust steam cone, a water inlet opening into said chamber above the axis of the exhaust steam cone, a water admission valve controlling said opening, and means controlled by the steam pressure in said live steam branch to open said water admission valve.
17. In an injector of the character described, a live steam cone and an exhaust steam cone, a steam chamber in communication with said exhaust steam cone, means for supplying said steam chamber with exhaust steam, a pressure pipe, a pipe adapted to be supplied with high pressure steam leading to a chamber communicating with said steam chamber, means for controlling the supply of steam to said chamber and said steam chamber in communication therewith, and means controlled by the high pressure steam in said pressure pipe for closing the communication for the exhaust steam leading to the steam chamber, when steam pressure is admitted to said pressure pipe.
18. In an injector of the character described, a live steam cone and an exhaust steam cone, a steam chamber in communication with said exhaust steam cone, means for supplying said chamber with exhaust steam, a pressure pipe adapted to be supplied with live steam leading to a room communicating with said steam chamber, means for controlling the communication with said pressure pipe, and means controlled by the steam pressure in said pressure pipe for closing the communication between the same and the room leading to the steam chamber, when steam pressure is admitted to the pipe.
19. In an injector of the character described, a live steam cone and an exhaust steam cone, a steam chamber in communication with said exhaust steam cone, means to supply said steam chamber with exhaust steam, an exhaust steam admission valve for controlling the admission of exhaust steam to the steam chamber, a pressure pipe in communication with the live steam supply and means for controlling said supply, said pressure pipe leading to a room in communication with the steam chamber, a chamber within said pressure pipe containing a valve capable of shutting off the communication with the steam chamber, and being in operative connection with the exhaust steam valve, said valve shutting the communication between the pressure pipe and the steam chamber and simultaneously opening the exhaust admission valve, when live steam under pressure is admitted to the pressure pipe.
20. In an injector of the character described, a live steam cone and an exhaust steam cone, an exhaust steam branch to supply exhaust steam to said exhaust steam cone, a non-return valve opening into said exhaust steam branch pressed upon its seat under a constant mechanical force and controlling said exhaust steam supply, a second non-return valve controlled by the live steam pressure cooperating therewith, each valve forming a stop for the other valve when resting upon its seat, the said second valve being only capable of being moved against its seat when the steam pressure applied to its surface exceeds the amount of constant mechanical force applied on the first valve.
21. In an injector of the character described, a live steam cone and an exhaust steam cone, a steam chamber in communication with said exhaust steam cone, an exhaust steam admission valve for controlling the exhaust steam supply to said steam chamber, said valve being held against its seat by constant mechanical force, a pressure pipe leading to said steam chamber and

- capable of being supplied with live steam under pressure, a controlling valve within said pressure pipe, adapted to shut the communication with the steam chamber, said controlling valve cooperating with the exhaust steam valve in such a manner that each of the valves forms a stop for the other valve, when resting upon its seat and being only able to shut the communication with the steam chamber, when the steam pressure in the pressure pipe and applied to its surface exceeds the amount of constant mechanical force applied on the exhaust steam valve.
- 10 22. In an injector of the character described, a live steam cone and an exhaust steam cone, a live steam branch leading to said live steam cone, a water chamber surrounding the exhaust steam cone, a chamber containing a steam pressure operated member controlling the water admission to said water chamber and a passage between said live steam branch and said chamber through which steam pressure can be applied to said member.
- 15 23. In an injector of the character described, a live steam cone and an exhaust steam cone, a live steam branch leading to said live steam cone, a water chamber surrounding the exhaust steam cone, a chamber containing a controlling member and a passage between the live steam branch and said chamber to allow the application of live

steam pressure to said member, the wall of said chambers having a passage between said chamber and the water chamber, said controlling member being adapted to shut said passage and to simultaneously open the water admission to said water chamber.

24. In an injector of the character described, a live steam cone and an exhaust steam cone, a live steam branch leading to said live steam cone, a water chamber surrounding the exhaust steam cone, a water admission valve controlling the water admission to said water chamber, a chamber containing a steam pressure controlled non-return valve in operative connection with said water admission valve, a passage between said live steam branch and said chamber to allow live steam under pressure to enter into said chamber, the wall of said chambers having an opening, between said valve containing chamber and the water chamber, said valve being capable of shutting said opening and of simultaneously opening the water admission valve, when steam pressure is admitted to said chamber.

In testimony whereof we have hereunto set our hands.
